PLANTER

Arthur F. Klingberg, McHenry, Ill., assignor to Bernard Edward Company, Chicago, Ill., a corporation of Illinois

Application September 27, 1952, Serial No. 21,621

Term of patent 3½ years

(Cl. D35—3)

To all whom it may concern:

Be it known that I, Arthur F. Klingberg, a citizen of the United States, and a resident of the city of McHenry, county of McHenry, State of Illinois, have invented a new, original, and ornamental Design for a Planter, of which the following is a specification, reference being had to the accompanying drawing, forming a part thereof, in which:

I claim:

The ornamental design for a planter, substantially as shown.

ARTHUR F. KLINGBERG.
